CLAIM

The ornamental design for a display screen with graphical user interface, as shown and described.

DESCRIPTION

This application is related to co-pending U.S. Provisional patent application Ser. No. 62/749,497 entitled "Methods and Systems for a Graphical User Interface of an Electronic Aviation Checklist", which was filed on Oct. 23, 2018 and is incorporated by reference in its entirety, and U.S. Design patent application Ser. No. 29/669,183 entitled "Display Screen With Graphical User Interface", which was filed on the same date as this application and is incorporated by reference in its entirety.

FIG. 1 is a front view of a display screen with graphical user interface showing our new design; and,

FIG. 2 is a second embodiment thereof.

The outer broken line perimeter showing the display screen and the broken lines within showing text and elements of the graphical user interface are provided for the purpose of illustrating portions of the article and form no part of the claimed design. The sections of the graphical user interface that have shading form a part of the claimed design and indicate a contrast of appearance or a contrast in color.
